FIG. 5

UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COOKING RETORT OVEN.

Application filed November 28, 1920, Serial No. 426,415. Renewed June 18, 1926.

This invention contemplates improvements of general utility in the coking retort oven art, and of especial utility in coking retort ovens of the well known Koppers cross-regenerative type exemplified in the patent to H. Koppers No. 818,083 dated April 17, 1906.

The invention has for an object the provision of a coking retort oven having, as an important characteristic, a ready adaptability for operation with producer gas as the oven fuel, and constructed so as to insure delivery of the entire volume of the producer gas supplied to the flame flues in which the gas is burned and to prevent waste of producer gas.

In addition to the general objects recited above, the invention has for other objects such other improvements or advantages in construction and operation as are found to obtain in the structures and devices herein-after described or claimed.

In the accompanying drawings, forming a part of this specification, and showing for purposes of exemplification a preferred form and manner in which the invention may be embodied and practiced, but without limiting the claimed invention to such illustrative instance or instances:

30 Figure 1 is a composite vertical section and elevation of a coking retort oven embodying features above specified and equipped with the improvements of the present invention, the sectional portion of the figure being taken on vertical planes longitudinally of the oven battery indicated by the lines D—D, F—F, E—E and G—G of Fig. 2;

40 Fig. 2 is a vertical section taken transversely through a heating wall of the coking retort oven;

Fig. 3 is a vertical section taken transversely through a coking chamber of the coking retort oven;

45 Fig. 4 is an enlarged fragmentary top plan view and horizontal section showing the construction of the fuel and exhaust mains and the connections between said mains and the oven; and

50 Fig. 5 is an enlarged vertical sectional elevation taken transversely through the pusher side of the oven and illustrating in detail the parts shown in plan in Fig. 4.

The same characters of reference indicate the same parts in each of the several views of the drawings.

In its present embodiment, the invention is incorporated in a small coking plant, having features of the well known Koppers cross-regenerative type, exemplified in the patent to H. Koppers hereinabove mentioned and in my prior Letters Patent of the United States for coking retort oven No. 1,416,322, dated May 16, 1922. My said prior patent relates to a coking retort oven having an extreme flexibility in operation exemplified in a ready adaptability of the oven for operation either with producer gas as the fuel or with coke oven gas burned in an atmosphere of ordinary preheated air, such as is utilized in ordinary coke ovens, or with coke oven gas burned in an atmosphere containing both air and a neutral gaseous diluent which is introduced into the combustion flues separately from the air. Because of the adaptability of the coke oven of my said prior patent for operation with producer gas as a fuel, the present invention is incorporated in such an oven, in which the invention is of particular utility. For convenience, the present description will be confined to this use of the invention; features of construction and operation are, however, readily susceptible of other valuable applications; consequently the scope of the invention is not confined to the specific use and specific embodiment hereinafter described as an illustrative example.

Referring to the drawings: there are illustrated sectional views of a coke oven battery or plant of the by-product type, such as has been hereinbefore mentioned, which coke oven battery embodies in its construction a plurality of crosswise elongated heating walls 11, 11 and a plurality of intermediate crosswise elongated vertical chambers or ovens 12, 12. The heating walls 11 form the side walls of the respective coking chambers 12, as shown more particularly in Fig. 1, and in the present instance are supported by the heavy supporting or pillar walls 13, 13, extending crosswise of the battery and located, as shown, beneath the respective heating walls 11. These pillar walls collectively form the main support for the entire superstructure of the battery and are themselves

firmly supported upon a flat mat or platform 14 which constitutes the sub-foundation on which the entire battery rests.

The coal to be coked is charged into the several coking chambers or ovens 12 through charging holes 15 located in the top 16 of the oven battery and positioned directly above the ovens or chambers 12, as shown in Fig. 3. These charging holes 15 are equipped with the usual removable covers, which are removed during charging of the several ovens and placed in position to close the tops of the ovens during the entire coking operation.

15 Heat for coking the charges of coal in the several ovens or chambers 12 is derived from the heating walls 11, which, as before mentioned, extend crosswise of the battery at the sides of the coking chambers. In the 20 present embodiment of the invention, each heating wall 11 is constituted of substantially triangular flame or combustion flues 17, of the general nature and arrangement disclosed in my said prior Patent No. 1,416,322, 25 which contains a complete description of the nature and mode of operation of these triangular flues. Hence, a detailed description of the flue construction is not essential to the present specification.

30 The crosswise regenerators 18 of the battery are located at a lower level than the aforesaid heating walls 11 and coking chambers 12, and, in the present instance, extend beneath the coking chambers 12 and between 35 the pillar walls 13. Below the middle lengthwise line of the heating walls, there is a partition 19, shown more particularly in Figs. 2 and 3, which extends all the way up from the mat of the battery to the bottom of the overlying coking chamber and from one to the other of the pillar walls 13. With this construction, there are thus 40 formed below each coking chamber and crosswise of the battery, two end to end regenerators 18, the meeting ends of which are 45 the partition 19 above mentioned.

Each regenerator 18 is a chamber containing open brickwork commonly called checkerwork and indicated at 20, with a distributing sole channel 21 underneath the checker-work of each regenerator, the channels 21 forming the soles of such chambers and opening up into the checkerwork of their respective regenerators. These regenerators 50 in alternation are heated by the hot combustion products that are exhausted from the flame or combustion flues hereinbefore mentioned and then impart such heat to the medium that they feed into these flame flues, 55 the preheated medium so fed into the flame flues varying in accordance with the character of oven operation, as will hereinafter appear.

In accordance with the present embodiment of the invention, the sole channels 21

of the regenerators on both sides of the longitudinal partition wall 19 extend from the same side of the battery to their respective regenerators, and the inflow and the outflow from the regenerators on both sides of such partition wall are all controlled from one side of the battery, preferably although not necessarily the pusher side. As shown in Fig. 1, the sole channels 21 are disposed in pairs, one sole channel of each 75 pair opening up into the checkerwork of a regenerator on the near side of the partition wall 19 and the other sole channel of such pair extending under the aforesaid regenerator and opening up into the checkerwork 80 of the regenerator on the far side of the partition wall.

The reversal in direction of flow through the several regenerators of the battery, and also through the flame or combustion flues 85 of the heating walls with which the regenerators communicate, takes place crosswise of the battery in accordance with the mode of operation employed in the patent to Koppers above mentioned. For example, all of the 90 regenerators 18 on one side of the partition 19 operate concurrently as inflow regenerators, while all of the regenerators on the other side of the partition 19 are operating 95 concurrently as outflow regenerators, and this is true notwithstanding the medium introduced into the several regenerators. On reversal, by means of the reversing devices hereinafter mentioned, all of the regenerators on the far side of the aforesaid partition 100 19 become inflow operating regenerators, while, at the same time, all of the regenerators on the near side of the said partition become outflow operating regenerators.

Each flue 17 of each heating wall has at 105 its top a port or opening 22 for draft and the passage of combustion products or waste gas from the flames within the flues. These ports 22 open up into horizontal flues 23 formed in the heating walls and connecting 110 all the flues on the pusher side of their respective heating walls with all the flues on the coke side of said heating walls.

In the operation of the battery, the several flues on one side of the longitudinal dividing line L operate as upburning flues, while concurrently the several flues on the other side of such dividing line operate as downburning or exhaust flues, the several flues 115 on each side of such dividing line exchanging functions on reversal of the oven. The horizontal channels or bus flues 23 just mentioned serve to direct the exhaust gases issuing from the ports 22 of the upburning flues into the similar ports of the downburning flues on the opposite side of the longitudinal dividing line. The draft through the ports 22 may be regulated by means of the usual movable dampers or sliding bricks 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

bottoms of the horizontal flues 23 and adapted to be reached by access flues 25 which extend from the top of the channels 23 in each heating wall to the top 16 of the battery, there being an access flue positioned over each flame or combustion flue of each heating wall.

Extending crosswise of the battery in each pillar wall 13 and located beneath the heating wall 11 thereabove, is a pair of gas supply channels 26 and 27, the channel 26 being located above the channel 27, as shown in Figs. 1 and 2. These channels 26 and 27 are for the purpose of supplying coke oven gas to the several flues on each side of the dividing partition L, and for this purpose, the channel 26 communicates with the individual flues 17 on the pusher side of the dividing line L by means of ducts 28 that lead from such channel 26 individually into the bottoms of individual flues; and the channel 27 which supplies the several flues 17 on the coke side of the dividing line L communicates therewith by means of similarly connecting ducts 29. Within the several ducts 28 and 29 are disposed the usual nozzles 30.

The supply of coke oven gas to the channels 26 and 27 of the respective heating walls 11 is derived from a coke oven gas main 31 located, in the present instance, on the pusher side of the battery, as shown in Figs. 2, 3 and 5, and extending longitudinally therewith. A series of supply connections, designated generally by the reference character 32 and conveniently of the general nature and arrangement disclosed in my before mentioned prior Patent No. 1,416,322, connects the coke oven gas main 31 with the several pairs of channels 26 and 27. A detailed description of the construction of such supply connections 32 is not thought to be necessary in the present specification and it will be sufficient to state that said supply connections 32 embody mechanism which operates, at each periodic reversal of the battery, to admit a supply of coke oven gas either to all of the channels 26 or to all of the channels 27 and to turn off the gas from the others. For example, while the channels 26 are receiving a supply of gas from the main 31, the channels 27 are shut off from such main and vice versa, in accordance with reversal in direction of flow through the flues 17, as hereinbefore explained.

The ducts by which the several regenerators communicate with the flues 17 are in their general arrangement similar to those disclosed in my prior Patent No. 1,312,301 dated August 5, 1919 and the prior patent to Joseph van Ackeren No. 1,312,372 dated August 5, 1919. Each regenerator communicates with the corresponding flues of the two heating walls adjacent to such regenerator by means of forked regenerator ducts 33, each extending first obliquely and then verti-

cally up into the heavy wall pillar 13, and then forking into two ascending ports 34, 35 that respectively open up into a pair of oppositely facing contiguous flues. These two branches of such forked duct become substantially vertical under the flue into which each becomes a port, and are so offset from the main channel of the duct, at its place of forking F, as to equalize the regenerator flow from such channel into and through such branches of the fork.

Referring now more particularly to Figs. 2, 3 and 4, the sole channels 21 of each pair of regenerators positioned endwise beneath a coking chamber respectively communicate with air ducts located, according to the present embodiment of the invention, on the pusher side of the battery, that is to say, the sole channel 21 of each regenerator on the coke side of the partition 19 communicates with a flow box 36, and each regenerator on the pusher side of the aforesaid longitudinal partition 19 communicates with a flow box 37; this results in the arrangement of two series of flow or air boxes 36 and 37 along the pusher side of the battery, the air box of the series 36 being respectively in communication with the pusher side regenerators and the air boxes 37 being respectively in communication with the coke side regenerators.

The several air boxes of the series 36 are provided with lids 38 for opening and closing the interior of the respective air boxes to the outer air, and the several air boxes of the series 37 are provided with similar lids 39. Each air box lid 38 is provided with a lid-operating lever 40 and each air box lid 39 is provided with a similar lid-operating lever 41. As shown in Fig. 4, the several air boxes of the series 36 are disposed in alternation with respect to the several air boxes of the series 37 and, as a result of this arrangement, the air boxes may be grouped into pairs, each pair comprising an air box 36 and an adjacent air box 37. The lid-operating levers 40 and 41 to alternate pairs H of such air boxes are controlled and operated by a single cable 42, whereas the lid operating levers 40 and 41 of the pairs K of the air boxes that are intermediate such alternate pairs of air boxes aforesaid are controlled and operated by a single cable 43.

The cables 42 and 43 are respectively provided with stops 44 and 45 suitably positioned therewith for engaging and operating the several levers 40 and 41 which they control, such stops being adapted on movement of the cables in one direction to engage certain of the aforesaid levers and operate them, while concurrently releasing other levers permitting the corresponding air box lids to remain in or be returned to closed position. Both the cables 42 and 43 are movable into three positions, i. e., into neutral, right and left positions. When either of the

cables 42 and 43 are in neutral position, the lids of all the air boxes that such cables control are in closed position. The operation of one of the cables to its left position, for example the cable 43, results in the opening of the lids of alternate air boxes of the series 36, whereas the lids of the series 37 that are controlled by such cable remain in closed position. Conversely, on movement of the same operating cable 43 toward the right, the lids of such air boxes of the series 37 as it controls are opened and the previously opened lids of air boxes of the series 36 are permitted to close. The other cable 42 controls the pairs of air boxes H, in exactly the same manner as has just been described. Consequently, by operating both cables simultaneously in the same direction all of the air boxes of either series 36 or 37 may be opened, this depending on whether the cables are moved to the right or left positions. Either cable, however, may be operated independently of the other and as each cable controls only alternate pairs of air boxes, the operation of one cable to right and left positions, while the other cable remains in neutral position, would result in opening the lid of only every fourth air box while the lids of all the other air boxes remain in closed position. The operating connections for the air boxes are thus capable of great flexibility of control, all of which is taken advantage of in the conversion of the oven operation into one of the several modes of operation, as hereinafter set forth.

Extending along the pusher side of the battery is a producer gas supply main 46 leading from a suitable source of supply of producer gas and adapted to be opened up to or shut off from its source of supply by means of any improved controlling valve. The valve that controls the supply to the producer gas main 46 is not herein illustrated for reason that the specific construction of such valve is wholly immaterial to the present invention. Leading into each air box of both series 36 and 37 is a branch supply pipe 47. Connected with the branch pipes 47 that feed the pairs H of air boxes are producer gas supply pipes 48 which are individually connected with the producer gas main 46 by means of vertical pipes 49. The vertical pipes 49 are provided with individual valves 50 for controlling the flow of producer gas into the branch pipes 47, with which such vertical pipes 49 are connected.

In accordance with the invention, two waste gas tunnels 51 and 52 extend longitudinally of the battery and merge at their discharge ends into a single tunnel 53 which leads to a stack 54. Within each of the tunnels 51 and 52 is a valve 55 permitting each tunnel to be opened up to or shut off from communication with the stack 54 as desired. Each air box of the series 36 is provided

with a port 56 that leads to a channel 57 which opens up into the aforesaid waste gas main 51; similarly each air box of the series 37 is provided with a port 58 leading to a channel 59 which communicates with the waste gas main 52. With this construction the waste gas main 51 is connected by channels 57 with the series of air boxes that control the exhaust from pusher side regenerators and the waste gas tunnel 52 is independently connected by a further series of channels with the air boxes that control the flow from the coke side regenerators. As none of the pusher side regenerators operates for outflow while the coke side regenerators are operating for inflow and vice versa, it is not essential that both of the waste gas tunnels 51 and 52 be concurrently connected with the stack 54, but only one of said tunnels 51 or 52 need be so connected, while the other is disconnected from the stack 54. Such connection or disconnection of the tunnels 51 and 52 with respect to the stack 54 may be readily accomplished by operation of the valves 55. By the invention, the entire group of inflow operating regenerators, whether the inflow is on the pusher or on the coke side of the battery, may be entirely shut off from the stack, with the result that the gaseous medium which flows into the inflow operating regenerators is altogether removed from any possible influence of the stack pull. This feature of the invention is of great advantage, particular when operating with producer gas for fuel, as will be hereinafter more fully explained in connection with the description of the operation of the battery.

The several air boxes of the series 36 are each provided with mushroom valves 60 for opening and closing the ports 56 with respect to the channels 57 leading to the waste gas tunnel 51; similarly the several air boxes of the series 37 are provided with mushroom valves 61 for opening and closing the ports 58 with respect to the channels 59 that lead to the waste gas tunnel 52. The mushroom valves 60 are operated by valve-operating levers 62 and the mushroom valves 61 by valve operating levers 63. All of the valve-operating levers of the series 62 are controlled and operated by a single cable 64 and similarly all of the valve-operating levers of the series 63 are controlled and operated by a single cable 65. Concurrently, by operation of the two controlling cables 64 and 65, during the reversal period hereinbefore mentioned, the several regenerators on one side of the longitudinal dividing line L are shut off from communication with the waste gas tunnel.

Extending longitudinally along the pusher side of the battery or plant, is a return waste gas or exhaust supply main 66, which is supplied with waste gas or products of combus-

tion discharged into the waste gas tunnel 53. Suitable connections may be provided for leading a portion of the waste gas from the tunnel 53 into the waste gas supply main 66, 5 said connections being preferably located at or in the vicinity of the stack. It is furthermore preferable to pass the waste gas from the tunnel 53 through a cooler of any approved construction before feeding such gas 10 into the waste gas supply main 66, as the gas in the tunnel 53 is still too hot, in most cases, for being fed back through the supply main 66 and subsequently into the valve control connections leading from said main 66. The 15 supply of waste gas to the main 66 may be opened up or shut off at will at the point where the main 66 is connected with the tunnel 53.

The air boxes of both series H and K are, 20 as before mentioned, individually provided with branch pipes 47 and such pipes 47 are severally connected with the aforesaid waste gas supply main 66 by means of vertical branches 67, shown more particularly in 25 Fig. 5. Each branch 67 is provided with its individual valve 68, permitting individual control of the flow from the main 66 into the several branch pipes 67. These branch pipes 67 are also respectively provided with 30 cable operated valves 69 having valve operating levers 70, as shown in Figs. 4 and 5. According to the present arrangement, the pairs of valves 69 corresponding to alternate pairs of air boxes of the series H are 35 opened when their valve operating levers 70 are moved in one direction whereas the pairs of valves 69 corresponding to the pairs of air boxes of the intermediate series K are opened only when their valve operating 40 levers 70 are moved in the opposite direction. All of the valve operating levers 70 that control the flow in the branches 47 leading into the entire series of air boxes 36 are operated by a single cable 71 and similarly all of the valve operating levers 70 45 that control the flow into the air boxes of the entire series 37 are operated by a single cable 72.

The operation of the battery, when using 50 a special generator gas, such as ordinary producer gas, as a fuel is as follows: the return waste gas main 66 is cut off from its source of supply of waste gas by a proper operation of the main controlling valve of 55 said main; the supply of coke oven gas to the coke oven gas main 31 is also shut off; the result is that both the return waste gas main 66 and the coke oven gas main 31 bear inoperative relations to the oven, in so far 60 as producer gas operation is concerned. A supply of producer gas is however turned on into the producer gas main 46, by opening the main valve of such producer gas main and the producer gas enters the vertical pipes 49 and passes into the branch 65 pipes 47 to the pairs of air boxes of the series H, from which branches the gas may flow into the regenerators 18 that operate to preheat the producer gas before delivering it into the combustion flues. Assuming 70 that the several regenerators of the pusher side group are operating as inflow regenerators and that the several regenerators of the coke side group are operating as outflow regenerators, it follows that the pusher side 75 flues 17 are concurrently operating as up-burning flues, while the coke side flues are operating as downflow waste gas flues and are delivering the waste gas or products of combustion into the coke side regenerators 80 through the system of ducts hereinabove mentioned. On the pusher side of the battery, regenerators through which an inflow of producer gas is maintained alternate with regenerators through which an inflow of 85 outside air is maintained, and consequently every flue receives a supply of both pre-heated air and preheated producer gas. During the period within which the regenerators and flues on the pusher side of the 90 battery are operating for upflow, the several controlling devices assume relative positions as follows: the mushroom valves of the entire series 61 are open thus communicably connecting the outflow operating coke side 95 regenerators with the channels 59 leading to the waste gas tunnel 52; on the other hand, the mushroom valves of the entire series 60 are closed to shut off communication between the air boxes of the series 36 and the 100 channels 57 leading into the waste gas tunnel 51. The gate valve 55 of the waste gas tunnel 51 is shut whereas the gate valve 55 of the waste gas tunnel 52 is open; consequently only those regenerators and air boxes, 105 in which outflow is being maintained, are subject to the stack pull, and the regenerators and air boxes which are operating for inflow are entirely shut off from any possible influence of the stack pull. The result 110 is that no air or producer gas which enters the air boxes of the series 36, operating for inflow, can be drawn past the closed mushroom valves of the series 60 into the stack and wasted. The air box lids 38 of the groups K are open whereas the air box lids 38 of the groups H are shut; the valves 69 of the air boxes 36 of the groups H are open 115 permitting inflow of producer gas into the several pusher side regenerators controlled by air boxes 36 of the groups H. Consequently atmospheric air and producer gas flows into each of the upburning flues on the pusher side of the battery, and burning upwardly passes through the horizontal bus flues 23 into the coke side flues. Thence the waste gases pass downwardly into the coke side regenerators and flowing outwardly 120 125

through the air boxes of the series 37 and the open mushroom valves 61 pass into the waste gas tunnel 52 to the stack 54.

On reversal of the battery, the coke side flues and regenerators are operated for inflow whereas the pusher side flues and regenerators are operated for outflow. During this period of operation, the entire series of air boxes 36 is connected with the waste gas tunnel 51 which is communicably connected with the stack 54 by opening its gate valve 55. The waste gas tunnel 52 is shut off from the stack by closing the valve 55 of said waste gas tunnel 52. The air boxes 37 of the group H are connected with the producer gas main whereas the air boxes 37 of the group K are opened up to the atmospheric air.

In operating the battery with coke oven gas in the ordinary manner, both the producer gas in the main 46 and the waste gas in the main 66 are shut off and at the same time both cables 71 and 72 are operated to positions to close the entire series of valves

69. On reversal of the battery from the pusher side to the coke side and vice versa, both air box lid controlling cables 42 and 43 are operated simultaneously in the same direction to open either the entire series of

air boxes 36 to the outer air or vice versa to open the entire series of air boxes 37 to the outer air, this depending on whether the inflow is maintained through the regenerators on the coke or pusher side of the battery.

75 The cables 64 and 65 are operated in alternation at the end of each reversal to connect either the entire series of air boxes 36 with the waste gas tunnel 51, or the entire series of air boxes 37 with the waste gas tunnel 52. When one of said waste gas tunnels is in communication with the stack the other is shut off from communication therewith in the manner hereinbefore described. When operating in this manner,

45 all of the regenerators on one side of the battery operate as air regenerators, while all of the regenerators on the other side of the battery operate in the usual way as outflow regenerators. On reversal the outflow regenerators become air regenerators and the air regenerators become outflow regenerators. The coke oven gas is turned on into the coke oven gas main 31 and the supply connections 32 are operated at each reversal

55 period to permit coke oven gas to flow to the upburning flues and concurrently to cut off the supply of coke oven gas from the downflow operating flues.

When burning coke oven gas as fuel, combined with a supply of neutral gaseous diluent to the upburning flues, the following is the mode of operation: the supply of producer gas to the producer gas main 46 is turned off and the supply of coke oven gas to the coke oven gas main 31 is turned on.

The reversal of coke oven gas to the flues on the opposite sides of the longitudinal dividing line L is effected in the same manner as in the ordinary coke oven gas operation just described. By operating the main controlling valve of the return waste gas main 66 a supply of cooled waste gas is permitted to flow from the waste gas tunnel 53 into said main 66. When one series of regenerators operate as air regenerators, the intermediate such air regenerators operate as return waste gas regenerators for supplying neutral gaseous diluent to the flues. This is accomplished by operating the valves 69 of alternate inflow operating regenerators in such manner as to connect these regenerators with the return waste gas tunnel 66. The outflow into the stack 54 is controlled in exactly the same manner as hereinabove described.

If desired, each waste gas tunnel 51, 52 may be provided with a damper 73, for controlling the outflow to the stack 54, when the valve 55 is open.

The invention as hereinabove set forth is embodied in a particular form of construction but may be variously embodied within the scope of the claims hereinafter made.

I claim:

1. In a coke oven battery, in combination: a plurality of horizontally elongated coking chambers arranged side by side; heating walls contiguous to such coking chambers and respectively constituted of vertical combustion flues; horizontally elongated regenerators located at a lower level than the coking chambers and the heating walls and parallel therewith, said regenerators being grouped into pairs crosswise of the battery and communicably connected with combustion flues of said heating walls; a producer gas main located on one side of the battery; reversing valve connections between said main and alternate pairs of said regenerators; reversing valve connections for connecting the pairs of regenerators that are intermediate such alternate pairs of regenerators with the outer air; a stack; a pair of waste gas tunnels located on the same side of the battery as said producer gas main and adapted to be communicably connected with said stack; valve connections between one of said tunnels and the pusher side regenerators on one side of the oven; valve connections between the other of said tunnels and the coke side regenerators on the opposite side of the oven; and controlling valve mechanism for communicably connecting one of said tunnels with the stack while shutting off the other from communication therewith; substantially as specified.

2. In a coke oven battery, in combination: a plurality of horizontally elongated coking chambers arranged side by side;

- heating walls contiguous to such coking chambers and respectively constituted of vertical combustion flues; horizontally elongated pusher and coke side regenerators on opposite sides of the oven located at a lower level than the coking chambers and the heating walls and parallel therewith and communicably connected with combustion flues of said heating walls; a producer gas main 10 located on one side of the battery; reversing valve connections between said main and some of said regenerators; reversing valve connections for connecting other regenerators with the outer air; a stack; a pair of waste gas tunnels both located on the same side of the battery as said main and adapted to be communicably connected with said stack; valve connections between one of said tunnels and the pusher side regenerators 15 on one side of the oven; valve connections between the other of said tunnels and the coke side regenerators on the opposite side of the oven; and controlling valve mechanism connecting one of said tunnels with the stack while shutting off the other from communication therewith; substantially as specified.
3. In a coke oven battery, in combination: a plurality of horizontally elongated coking 20 chambers arranged side by side; heating walls contiguous to such coking chambers and respectively constituted of vertical combustion flues; horizontally elongated regenerators located at a lower level than the coking 25 chambers and the heating walls and parallel therewith, said regenerators being grouped into pairs crosswise of the battery and communicably connected with combustion flues of said heating walls; a producer 30 gas main; reversing controlling connections between said main and alternate pairs of such regenerators; reversing valve connections for connecting the pairs of regenerators that are intermediate such alternate 35 pairs of regenerators with the outer air; a stack; a pair of waste gas tunnels both located on one side of the battery and adapted to be communicably connected with said stack; valve connections between one of said 40 tunnels and the pusher side regenerators on one side of the oven; valve connections between the other of said tunnels and the coke side regenerators on the opposite side of the 45 oven; and controlling valve mechanism for communicably connecting one of said tunnels with the stack while shutting off the other from communication therewith; substantially as specified.
4. In a coking retort oven, in combination: a plurality of horizontally elongated coking 50 chambers arranged side by side; flued heating walls contiguous to such coking chambers; horizontally elongated crosswise regenerators for gas and air, operating alternately for inflow and for outflow, said gas and air regenerators being alternately disposed longitudinally of the battery and communicably connected with said flued heating walls; a produced gas main communicably connected with all the gas regenerators; a 55 stack; a pair of waste gas tunnels both located on one side of the battery and adapted to be communicably connected with said stack and with said regenerators; and means for communicably connecting with the stack the waste gas tunnel that is in communication with the outflow operating regenerators, while shutting off from the stack the waste gas tunnel that connects with the inflow operating regenerators; substantially as 60 specified.
5. In a coking retort oven, in combination: a plurality of horizontally elongated coking 65 chambers arranged side by side; flued heating walls contiguous to such coking chambers; horizontally elongated crosswise regenerators for gas and air, operating alternately for inflow and for outflow, said gas and air regenerators being alternately disposed longitudinally of the battery and 70 communicably connected with said flued heating walls; a producer gas main communicably connected with the gas regenerators; a stack; a pair of waste gas tunnels both located on the same side of the battery 75 as said producer gas main and adapted to be communicably connected with said stack and with said regenerators; and means for communicably connecting with the stack the waste gas tunnel that is in communication 80 with the outflow operating regenerators, while shutting off from the stack the waste gas tunnel that connects with the inflow operating regenerators; substantially as specified.

JOSEPH BECKER.
